LEER CONSTRUCTION

John L. Drake, Toledo, Ohio, assignor to Libbey-Owens-Ford Glass Company, Toledo, Ohio, a corporation of Ohio

Application March 23, 1934, Serial No. 717,065

14 Claims. (CL. 49—47)

The present invention relates broadly to annealing leers and more particularly to those adapted primarily for the annealing of sheet glass, although of course not necessarily restricted to such use.

In certain types of sheet glass producing apparatus, the sheet, after being formed, is passed slowly in a generally horizontal direction through a relatively long annealing leer in the form of a substantially closed tunnel-like chamber or oven. The sheet is carried through the leer upon any suitable conveying means such as, for example, a series of spaced horizontally aligned driven rolls. Suitable heaters, placed at intervals within the leer, serve to regulate the temperature at different portions from end to end thereof so that the sheet will be gradually cooled and tempered.

When rolls are employed as the sheet conveying means, the opposite side walls of the leer are provided with openings through which the said rolls are adapted to be inserted and removed and also through which the leer roll shafts extend; the supporting and driving means for the said rolls being located exteriorly of and along opposite sides of said leer. Unless these openings at the ends of the leer rolls are suitably closed or sealed, unequal heat losses will result therefrom which will create disturbing temperature conditions within the leer and adversely affect the proper annealing of the sheet. In order to obviate these disadvantages, various means have been proposed for closing or sealing these openings, but which do not completely fulfill the desired purpose, in that with all prior arrangements, a relatively large amount of heat has been lost at the openings, due in a large measure to the fact that the closure means for the said openings were of such construction that they acted as conductors to carry the heat from the interior of the leer to the exterior thereof where it was radiated to the atmosphere.

The primary aim and object of this invention, therefore, resides in the provision of an annealing leer of the above general character embodying novel and improved means for effectively closing or sealing the openings in the side walls of the leer at the opposite ends of the rolls which will serve to reduce to a minimum loss of heat at these points as well as prevent the ingress of cold air and drafts.

Other objects and advantages of the invention will become more apparent during the course of the following description when taken in connection with the accompanying drawings.

In the drawings wherein like numerals are employed to designate like parts throughout the same,

Fig. 1 is a transverse section through an annealing leer constructed in accordance with the present invention.

Fig. 2 is a side elevation of a portion of the leer.

Fig. 3 is a horizontal section taken substantially on line 3—3 of Fig. 2.

Fig. 4 is a perspective sectional view through one side wall of the leer.

Fig. 5 is a vertical section taken substantially on line 5—5 of Fig. 2.

Fig. 6 is a vertical section taken substantially on line 6—6 of Fig. 2, with the casing partially broken away to show the arrangement of the insulating material at the sides of the openings.

Fig. 7 is a perspective sectional view of a modified type of casing, and

Fig. 8 is a horizontal section through a portion of the leer of Fig. 7.

With reference now to the drawings and particularly to Figs. 1 to 6 inclusive, the annealing leer illustrated therein is of the so-called "tunnel type" including a bottom 10, side walls 11 and 12, and a top 13. The leer is adapted to be heated in any preferred or well known manner and the glass sheet 14 or other article to be annealed is carried relatively slowly therethrough upon a series of horizontally aligned rotatable rolls 15.

For the purpose of facilitating the positioning of the rolls 15 within the leer and for removal therefrom, the opposite side walls 11 and 12 are provided with opposed openings 16 and 17 respectively through which the shafts 18 of the leer rolls 15 extend. These shafts are suitably mounted and driven by means not shown but which is arranged along opposite sides of the leer exteriorly thereof.

Each side wall structure 11 and 12 of the leer comprises an exterior brick wall 19 and an inner wall 20 preferably of fire brick, said inner and outer walls being spaced from one another and having arranged therebetween suitable insulating material 21. The top 13 of the leer is also preferably insulated by inserting between the upper and lower layers of brick 22 and 23 respectively, suitable insulation 24. By insulating the side walls and top of the leer in this manner, loss of heat by radiation from the leer will be materially lessened.

As brought out above, it is desirable and in fact essential to the proper annealing of the glass

sheet 14, or other articles being treated, that the openings 16 and 17 at opposite ends of the leer rolls be closed or sealed to prevent unequal heat losses as well as the admission of cold air and drafts. Also, that the means heretofore provided for this purpose have not proven entirely satisfactory in that, due to their particular construction and arrangement, considerable heat has been lost at the openings. It is the aim, 10 therefore, of the present invention to provide novel and improved means not only for effectively closing the openings, but which is of such construction and arrangement as to reduce to a minimum loss of heat from the leer at these 15 points to the end that more even and uniform temperature conditions may be maintained within the leer and, as a consequence, better annealing obtained.

In accordance with this invention, there is 20 inserted within each of the openings 16 and 17 in the side walls 11 and 12 respectively of the leer a casing or collar 25 preferably of metal and substantially rectangular in cross section, said casing forming a lining for the said opening. The casing 25 is constructed of two parts 25 or sections 26 and 27 arranged in end to end relationship with respect to one another transversely of the leer. The two casing sections 26 and 27 are, however, entirely separate from and 30 are not adapted to contact with one another at any point. Each section of the casing preferably extends substantially one-half the length of the respective opening 16 or 17, the outer section 26 being disposed opposite the exterior wall 35 19 and provided at its outer end with a lateral flange 28, while the inner section 27 is disposed opposite the inner wall 20 and provided with a lateral flange 29.

The inner adjacent ends of sections 26 and 27 40 of casing 25 are formed with a plurality of spaced fingers which are adapted to interengage one another in non-contacting relationship. Thus, the top and bottom walls of the section 26 are provided with a plurality of 45 spaced flat fingers 30 and the section 27 with a plurality of similar fingers 31, the fingers of one section being received within the spaces formed between the fingers of the other section, it being noted upon reference to Figs. 3 and 4 that the 50 fingers 30 and 31 do not contact with one another.

The opposite side walls of the casing sections 26 and 27 are also provided with a plurality of 55 interlocking fingers 32 and 33 respectively substantially similar to fingers 30 and 31 in that the fingers of one section fit between the fingers of the other section, with the two sets of fingers being spaced from one another as clearly illustrated in Figs. 1 and 4.

As best shown in Figs. 3 and 6, the insulating material disposed within the side walls of the leer between adjacent openings 16 and 17 is divided into or made up of three vertical columns or strips 34, 35 and 36 disposed side by side 60 transversely of the leer. The fingers 32 formed on casing section 26 are provided with laterally and outwardly turned end portions 37 which are received between the central strip of insulating material 35 and the outer strip 36, while the 65 fingers 33 carried by section 27 are also formed with laterally and outwardly turned end portions 38 received between the central strip of insulating material 35 and the other outer strip 34.

70 The top and bottom walls of the casing section

26 are also provided intermediate their inner and outer ends with flanges 39 received between the exterior leer wall 19 and insulation 21, while the top and bottom walls of casing section 27 are likewise provided with similar flanges 40 received between the inner leer wall 20 and insulation 21. The casings 25 of course serve to maintain the insulating material 21 in place.

I am aware of the fact that metallic casings or collars have heretofore been used in the 10 openings in the side walls of the leer in surrounding relation to the leer roll shafts. However, in all of these instances, the casing was of a one-piece construction and extended completely through the opening so that the inner 15 end of the said casing was exposed to the interior of the leer and the outer end thereof to the atmosphere. As a result, these casings acted as conductors to carry a large amount of heat from the interior of the leer to the exterior 20 thereof where it was radiated to the atmosphere. In consequence, considerable heat was lost from the leer at these points resulting in the setting up of ununiform and undesirable temperature conditions within the leer which 25 had a detrimental effect upon the annealing operation. By the provision of the improved two-part type of casing herein provided, however, loss of heat from the leer at the leer roll openings is reduced to a minimum due to the fact 30 that there is no direct contact between the two casing sections 26 and 27, these two sections being slightly spaced from one another. In other words, the casing section 26 exposed to the atmosphere is not connected to the casing 35 section 27 exposed to the interior of the leer.

In practice, after the leer rolls 15 have been properly mounted within the leer, the openings through the casings 25 are adapted to be closed or sealed and this may be effected by inserting 40 within the said casings a plurality of fire bricks 41, and the small space left between the bricks and roll shaft may be plugged up by clay or some other suitable material 42. The bricks 41 are preferably arranged within the inner section 45 27 of the casing opposite the interior leer wall 20 as shown in Fig. 1.

At any one or more desired locations along the leer, the opposed casings may be made of such 50 size as to accommodate two leer rolls and of such construction as to provide between the openings for the roll shafts an opening through which the interior of the leer may be observed by the operator. Upon reference particularly to Figs. 2, 3 and 5, there is disclosed a double casing designated in its entirety by the numeral 25', said casing being substantially of the same construction as the single casings 25 and comprising an outer section 26' and an inner section 27', the 55 inner adjacent ends of said sections being formed with a plurality of spaced fingers which interengage one another in non-contacting relationship. The double casing 25' forms the lining of an opening in the leer wall and through which extends the two leer roll shafts 18' and 18" (Fig. 2).

The double casing 25' is provided intermediate its ends with two spaced vertical walls which provide therebetween an opening through which the operator can look into the leer to check the 70 operation thereof. The vertical walls carried by the outer casing section 26' are designated 43—43 while the vertical walls carried by inner casing section 27' are designated 44—44, the walls 43 and 44 being arranged in alignment with one 75

another and formed at their inner adjacent ends with a plurality of flat fingers 45 and 46 respectively (Fig. 5) which interengage but are spaced from one another. The opening between the 5 vertical walls 43-43; 44-44 may be closed by a removable cover plate 47 having a handle 48 attached thereto. The walls 43-43 and 44-44 define the inner walls of the openings through which the roll shafts 18' and 18" project. Each 10 of these openings is also adapted to be closed or sealed by a plurality of fire bricks 41 inserted therein and the space between the bricks and roll shafts plugged up by clay or the like 42.

In Figs. 7 and 8 has been illustrated a slightly 15 modified type of casing designated in its entirety by the numeral 49, said casing being also of two-part construction and comprising an outer section 50 and an inner section 51. The inner adjacent ends of the top and bottom walls 20 of the casing sections 50 and 51 are preferably formed with substantially straight parallel edges 52 and 53 spaced slightly from one another. On the other hand, the opposite side walls of the 25 two casing sections are formed at their inner adjacent ends with tapered fingers 54 and 55 respectively, with the fingers of one section being received within the spaces between the fingers of the adjacent section. As shown, these fingers are arranged in spaced relationship and 30 do not contact with one another.

When using this type of casing, the insulating material 21 disposed in the side walls of the 35 leer between adjacent openings is formed in a single strip or column 56. The fingers 54 of casing section 50 are provided with laterally and outwardly turned end portions 57 which are received between the insulating material 56 and inner brick wall 20, while the fingers 55 of casing section 49 are also provided with laterally 40 and outwardly turned end portions 58 received between the insulation 56 and exterior brick wall 19. The objects of and advantages to be gained from the use of this form of casing are substantially the same as those ascribed to that 45 form of the invention illustrated in Figs. 1 to 6.

It is to be understood that the form of the 50 invention herewith shown and described is to be taken as the preferred embodiment of the same, and that various changes in the shape, size and arrangement of parts may be resorted to without departing from the spirit of the invention or the scope of the subjoined claims.

I claim:

1. An annealing leer of the character described including a bottom, side walls, and a top, said side walls being provided with openings therein, rolls mounted within the leer for carrying the work to be annealed therethrough, with the said rolls projecting at their opposite ends 55 through said openings, casings arranged within the openings and forming linings therefor, and means arranged within said casings in surrounding relation to said rolls for closing the said openings, each casing being formed of a plurality 60 of sections arranged end to end transversely of the leer and spaced from one another.

2. An annealing leer of the character described 70 including a bottom, side walls, and a top, said side walls being provided with openings therein, rolls mounted within the leer for carrying the work to be annealed therethrough, with the said rolls projecting at their opposite ends through said openings, metallic casings arranged within the openings and forming linings therefor, and 75 refractory means arranged within said casings

in surrounding relation to said rolls for closing the said openings, each casing being formed of a plurality of sections arranged end to end transversely of the leer and spaced from one another.

3. An annealing leer of the character described 5 including a bottom, side walls, and a top, said side walls being provided with openings therein, rolls mounted within the leer for carrying the work to be annealed therethrough, with the said 10 rolls projecting at their opposite ends through said openings, casings arranged within the openings and forming linings therefor, and means arranged within said casings in surrounding relation to said rolls for closing the said openings, each casing being formed of a plurality of sections arranged end to end transversely of the 15 leer and provided with portions which interengage but are spaced from one another.

4. An annealing leer of the character described 20 including a bottom, side walls, and a top, said side walls being provided with openings therein, rolls mounted within the leer for carrying the work to be annealed therethrough, with the said 25 rolls projecting at their opposite ends through said openings, metallic casings arranged within the openings and forming linings therefor, and refractory means arranged within said casings in surrounding relation to said rolls for closing the said 30 openings, each casing being formed of a plurality of sections arranged end to end transversely of the leer and provided with portions which interengage but are spaced from one another.

5. An annealing leer of the character described 35 including a bottom, side walls, and a top, said side walls being provided with openings therein, rolls mounted within the leer for carrying the work to be annealed therethrough, with the said 40 rolls projecting at their opposite ends through said openings, metallic casings arranged within the openings and forming linings therefor, and means arranged within said casings in surrounding relation to said rolls for closing the said 45 openings, each casing being formed of a pair of sections arranged end to end transversely of the leer and provided at their inner adjacent ends with a plurality of spaced fingers, with the fingers of one section being received between the 50 fingers of the adjacent section and spaced therefrom.

6. An annealing leer of the character described 55 including a bottom, side walls, and a top, said side walls being provided with substantially rectangular openings therein, rolls mounted within the leer for carrying the work to be annealed therethrough, with the said rolls projecting at their opposite ends through said openings, substantially rectangular metallic casings arranged 60 within the openings and forming linings therefor, and means arranged within said casings in surrounding relation to said rolls for closing the said openings, each casing being formed of a pair of sections arranged transversely of the leer and spaced from one another, the top, bottom, and side walls of each casing section being provided 65 at its inner end with a plurality of spaced fingers, with the fingers of one section being received between the fingers of the adjacent section.

7. An annealing leer of the character described 70 including a bottom, side walls, and a top, said side walls being provided with openings therein and each side wall structure comprising inner 75 and outer spaced walls and insulating material

disposed therebetween, rolls mounted within the leer for carrying the work therethrough, with the said rolls projecting at their opposite ends through said openings, metallic casings arranged 5 within the openings and forming linings therefor, and means arranged within said casings in surrounding relation to said rolls for closing the said openings, each casing being formed of a plurality of sections arranged end to end transversely of the leer and spaced from one another.

8. An annealing leer of the character described including a bottom, side walls, and a top, said side walls being provided with openings therein and each side wall structure comprising inner 15 and outer spaced walls and insulating material disposed therebetween, rolls mounted within the leer for carrying the work therethrough, with the said rolls projecting at their opposite ends through said openings, metallic casings arranged 20 within the openings and forming linings therefor, and means arranged within said casings in surrounding relation to said rolls for closing the said openings, each casing being formed of a plurality of sections arranged end to end transversely of the leer and provided with portions which interengage but are spaced from one another.

9. An annealing leer of the character described including a bottom, side walls, and a top, said side walls being provided with openings therein and each side wall structure comprising inner and outer spaced walls and insulating material disposed therebetween, rolls mounted within the leer for carrying the work therethrough, with the said rolls projecting at their opposite ends through said openings, metallic casings arranged within the openings and forming linings therefor, and means arranged within said casings in surrounding relation to said rolls for closing 30 the said openings, each casing being formed of a pair of sections arranged end to end transversely of the leer and provided at their inner adjacent ends with a plurality of spaced fingers, with the fingers of one section being received 35 between the fingers of the adjacent section and spaced therefrom.

10. An annealing leer of the character described including a bottom, side walls, and a top, said side walls being provided with openings 50 therein and each side wall structure comprising inner and outer spaced walls and insulating material disposed therebetween, rolls mounted within the leer for carrying the work therethrough, with the said rolls projecting at their opposite ends through said openings, metallic casings arranged within the openings and forming linings therefor, and means arranged within said casings in surrounding relation to said rolls for closing the said openings, each casing being 55 formed of a pair of sections arranged end to end transversely of the leer and provided at their inner adjacent ends with a plurality of spaced fingers, with the fingers of one section being received between the fingers of the adjacent section and spaced therefrom, the fingers at the sides of the openings being provided with portions engaging the insulating material.

11. An annealing leer of the character described including a bottom, side walls, and a top, said side walls being provided with openings therein and each side wall structure comprising inner and outer spaced walls and insulating material disposed therebetween, rolls mounted within the leer for carrying the work

therethrough, with the said rolls projecting at their opposite ends through said openings, substantially rectangular metallic casings arranged within the openings and forming linings therefor, and refractory means within the casings in surrounding relation to said rolls for closing the said openings, each casing being formed of two sections arranged end to end transversely of the leer and spaced from one another, the top, bottom, and side walls of each casing section 10 being provided at its inner end with a plurality of spaced fingers, with the fingers of one section being received between the fingers of the adjacent section, and the fingers at the sides of the casing sections engaging the insulating material provided between adjacent openings.

12. An annealing leer of the character described including a bottom, side walls, and a top, said side walls being provided with openings therein and each side wall structure comprising inner and outer spaced walls and insulating material disposed therebetween, rolls mounted within the leer for carrying the work therethrough, with the said rolls projecting at their opposite ends through said openings, substantially rectangular metallic casings arranged within the openings and forming linings therefor, and refractory means within the casings in surrounding relation to said rolls for closing the said openings, the insulating material between adjacent openings consisting of three vertical strips arranged side by side transversely of the leer, each casing being formed of two sections arranged in end to end relation and provided at their inner adjacent ends with a plurality of fingers which interengage but are spaced from one another, the fingers at the sides of one casing section being provided with laterally turned end portions received between the central strip of insulating material and one outer strip, while the fingers at the sides of the other casing section are also provided with laterally turned end portions received between the central strip of insulating material and the other outer strip.

13. An annealing leer of the character described including a bottom, side walls, and a top, said side walls being provided with openings therein, conveying means mounted within the leer for carrying the work to be annealed therethrough, with a portion of the conveying means projecting through said openings, casings arranged within the openings and forming linings therefor, and means arranged within said casings for closing the said openings, each casing being formed of a plurality of sections arranged end to end transversely of the leer and spaced from one another.

14. An annealing leer of the character described including a bottom, side walls, and a top, said side walls being provided with openings therein, conveying means mounted within the leer for carrying the work to be annealed therethrough, with a portion of the conveying means projecting through said openings, casings arranged within the openings and forming linings therefor, and means arranged within said casings for closing the said openings, each casing being formed of a plurality of sections arranged end to end transversely of the leer and provided with portions which interengage but are spaced from one another.
